UNITED STATES PATENT OFFICE.

KLAS GUSTAV BLOMBERG, OF SÖDERTÄLJE, AND BENGT AUGUST PETTERSSON, OF LIDKÖPING, SWEDEN.

MACHINE FOR PRODUCING SPRING DRESS-FASTENERS.

1,382,463.

Specification of Letters Patent. Patented June 21, 1921.

Application filed October 17, 1919. Serial No. 331,515.

To all whom it may concern:

Be it known that we, KLAS GUSTAV BLOMBERG, a subject of the King of Sweden, residing at Södertälje, in the Province of

5 Södermanland and Kingdom of Sweden, and BENGT AUGUST PETTERSSON, a subject of the King of Sweden, residing at Lidköping, in the Province of Västergötland and Kingdom of Sweden, have invented new and useful 10 Improvements in Machines for Producing Spring Dress-Fasteners, for which we have filed an application in Sweden on September 17, 1918, and of which the following is a specification.

15 The invention described in the following consists of an arrangement in connection with machines used in the production of dress fasteners, the particular purpose of the device being to cut out the top section of the 20 fastener and to bend down the edge of same.

The constructional features of the invention are made clear in the annexed drawing, in which Figure 1 shows the part of the machine which is used for stamping out and 25 bending down edge of the top section of the fastener from the side; Fig. 8 being a plan view, and Fig. 2 a vertical sectional drawing of same. Figs. 3-7 show five different positions of the tools used in the cutting-out and 30 bending while in operation.

1, 2, and 3 are three concentric plungers guided in a tube or sleeve 6, which is fastened to a table 18. The plungers are each connected to one end of respectively levers 35 11, 12, and 13 which impart a reciprocating movement to the plungers. The opposite ends of levers 11 and 13 are provided with rollers 27 and 28 which are brought in contact with cams 15 and 17 by means of the 40 springs 29 and 30 fastened to the levers; the cams being fitted on shaft 14 which latter during rotation produces the oscillating movement of the levers 11 and 13. The lever 12 obtains its oscillating motion from an eccentric 45 fastened to the shaft 14, the eccentric strap 31 of same being connected to the lever 12 by the rod 32.

The sleeve 6 which incases the plungers 1, 2 and 3 is fitted in the upper end with a 50 cut-out pillow die 5 which acts in conjunction with a cut-out die 4 fitted to the plunger 1. A pillow die 8 is fitted above the cut-out die 5 and operates in conjunction with a drawing die 7 attached to the plunger 2. On the center plunger 3 is a spring

41 which forces up a pin 9, the function of which is to push off the fastener from the drawing die 7.

Between the sleeve 6 and the cut-out pillow die 5 is a space 33, (Fig. 3) provided 60 for the metal strip 26 out of which the fasteners are to be cut.

Fitted to the sleeve 6 are scrap metal shears 19, 20 of which the lower blade 19 is fitted into the sleeve 6 and is adjustable in a 65 vertical direction by means of wedge 34. The top blade of the shears 20 has one end movably attached to the sleeve 6 by means of a screw 35 and is carried in the other end by a guide 36. The top blade of the shears 70 20 is moved up and down by two collars 22, 23 which are fitted to a rod 21 placed on one side of the appliance and having a sliding movement in a vertical direction.

On one side of the sleeve 6 is a trough or 75 channel 24 which is attached to an arm 37 which is brought in contact with a cam 39 on the shaft 14 by means of a roller 38 whereby a reciprocating motion is imparted to the arm 37 and the channel 24 during the 80 rotation of the shaft.

A hole 25 is provided in the table 18 and in the hole is fitted a scrap metal rake 10 which receives a vertical reciprocating motion from the arm 37 fitted to the rake. 85

The above described arrangement operates in the following manner, to wit:—

The metal strip 26 after having been previously treated in the press tool enters in the position shown in Fig. 3, with the knob 90 that has been pressed into the strip directly over the opening of the sleeve 6, which incases the plungers, and underneath the cut-out pillow 5. The outside plunger 1 is thereupon moved upward and stamps out the fastener (Fig. 4). Immediately afterward the intermediate plunger 2 is moved upward with its drawing die 7 and carries the fastener to the pillow die 8 (Fig. 5) which has a taper hole and causes the edges of the fastener to be bent around the drawing die. Upon the fastener being removed from the drawing pillow die a pin 43 attached to a conveyer—which is more closely described in application No. 331,511 as pin 3—is inserted in the knob simultaneously with the center plunger rod being carried upward and thereby causing the fastener blank to be pushed off from the drawing die 7 by means of the push-off pin 9 fitted to the rod. The 110

scrap metal cut off from the strip 26 by the shears 19, 20 drops down in the channel 24, and the reciprocating motion of the channel carries the scrap to the hole 25 where it is caught by the rake 10.

We claim.

A device for cutting out the top section of a dress fastener and bending down the edges of same in a machine for producing such 10 fasteners, consisting of three concentrically fitted plungers (1, 2, 3), three rocking levers (11, 12, 13) which latter impart a ver-

tical reciprocating motion to the said plungers, a cut-out die pillow (5) acting in conjunction with cut-out die (4) fitted to the outside plunger (1) a drawing die pillow (8) acting in conjunction with drawing die (7) fitted to the intermediate plunger (2), a spring push-off pin (9) fitted to the center plunger (3) with the object of pushing the 15 fastener blank (40) off the drawing die (7).

KLAS GUSTAV BLOMBERG.
BENGT AUGUST PETTERSSON.
